COMB

Philip B. Schoen, 7301 N. Sheridan Road, Chicago, Ill.

Filed Aug. 30, 1960, Ser. No. 61,952

Term of patent 14 years

(Cl. D86—8)

Fig. 1 is a front elevational view of a comb embodying my new design.

Fig. 2 is a side elevational view thereof as seen from the right of Fig. 1.

Fig. 3 is a sectional view taken along the line 3—3 of Fig. 1 and looking in the direction of the arrows.

I claim:

The ornamental design for a comb, substantially as shown.
